Attorney.

UNITED STATES PATENT OFFICE.

ORLANDO C. KETRING, OF MONTEZUMA, OHIO.

SASH-FASTENER.

SPECIFICATION forming part of Letters Patent No. 378,794, dated February 28, 1888.

Application filed November 12, 1887. Serial No. 255,015. (No model.)

To all whom it may concern:

Be it known that I, ORLANDO C. KETRING, a citizen of the United States of America, residing at Montezuma, in the county of Mercer 5 and State of Ohio, have invented certain new and useful Improvements in a Sash Stop and Lock; and I do hereby declare the following to be a full, clear, and exact description of the invention, such as will enable others skilled in 10 the art to which it appertains to make and use the same, reference being had to the accompanying drawings, and to letters or figures of reference marked thereon, which form a part of this specification.

15 My invention relates to improvements in combined sash stops and locks; and it consists in the novel construction and arrangements of the parts thereof, which will be more fully hereinafter described, and particularly pointed 20 out in the claim.

The object of my invention is to provide a 25 double fastening in combination with a sash of a window-frame which is capable of a positive locking action or a temporary retaining connection, the parts being of simple construction and operation, strong and durable, easily handled, and readily understood and operated. I attain these objects by the construction illustrated in the accompanying drawings, wherein 30 like letters of reference indicate similar parts in the several views, in which—

Figure 1 is a view in elevation of a portion 35 of the window frame and sash, shown broken away and with my improvement in section mounted in connection therewith. Fig. 2 is a perspective view in detail of the positively-acting locking-bolt and spring-actuated plate.

A indicates the sash, and B the window-frame. A suitable recess, a, is formed in the 40 window-frame for the reception of the casing C of my improved locking device, suitable smaller recesses, a', extending from the main recess a to give free play and action to parts of the mechanism.

45 Two rivets or bolts, D D, are disposed in opposite sides of the casing C, and are connected at their inner ends to the said housing or frame C and at their opposite ends to a spring-actuated plate, E, which has inwardly-curved ends, 50 which will prevent any tendency of the sash cramp in raising or lowering the same by binding against the frame. The inner ends of the

bolts D move through the inner side of the housing or frame C into the recesses a' when the lock is operated. The said bolts D are encircled by coiled springs S S, which have bearings at each end against the housing or frame C and the spring-plate E, respectively, as shown.

The inner face of the spring-actuated plate 60 E has a collar, E', formed integrally therewith, which is constructed with a longitudinal slot, e, and transverse or circumferential slots e'. A bolt, F, having a thumb-piece, f, and a collar, f', with a lug, f'', is passed through the 65 collar E'. The lug f'' working in the longitudinal slot e, when the said bolt is directly actuated, the end of the said bolt F projects through the spring-actuated plate E and engages with a socket, F', mounted in the window-frame. A series of these sockets may be disposed at various elevations, as will be readily understood. When the bolt F is in engagement with any one of the sockets F', it may be permanently locked in said position 70 by turning the said bolt F, so that the lug f'', formed on the collar f, can be turned either to one side or the other and engage with the transverse or circumferential recesses e' nearest the spring-actuated plate E. If, however, 75 it is desired that the bolt F is to be disposed in permanent disengagement, it is drawn inward, so that the lug f'' of the collar f will engage with the inner recess, e', of the collar E'. A coiled spring, S', encircles the bolt F, and 80 has a bearing at one end against the collar f and at the opposite end against the casing or frame C. By this construction connection, when the bolt is released from either of the recesses e', it will be shot forward into the casing or window-frame to engage the socket F'. 85

It will be understood that the turning or withdrawal of the bolt F is accomplished by an inner thumb-piece or operating-knob.

If the bolt F is drawn inward and turned so 90 as to permit the lug f'' on the collar f' to engage with the inner recesses, e', in the collar E', the frictional contact of the spring-plate E will be brought to bear against the window-frame B and retain the sash in an elevated position. When the lug f'' is in engagement with the transverse or circumferential slot e' in the collar E', adjacent to the spring-actuated plate E, the bolt and the plate may be drawn in- 95 100

wardly simultaneously, as will be readily understood. By this double construction of fastening, adapted to be operated conjointly or independently, a fastening is provided which 5 will still have operation if either one or the other of the parts should become broken or displaced, and the window still be provided with a fastening device. I consider this an advantage of great importance, in view of the fact 10 that many of the fastenings used upon car-windows especially are liable to become broken or displaced by the jarring movement of the cars, and often present inconveniences to the traveling public in hoisting or elevating the 15 windows, on account of the displacement of the locks or catches. By the use of my improvement I almost entirely obviate this difficulty.

The novelty and utility of my improved device being apparent, it is unnecessary to enlarge upon the same herein.

I claim—

The combination of the housing or supporting frame, the bolts D, movable in said frame and encircled by coiled springs, a spring-actuated plate, E, secured to said bolts and formed with inwardly-curved ends and provided with an integral collar, E', provided with longitudinal and transverse slots e and e', the centrally-situated spring-encircled bolt F, and the collar f' on said bolt having a lug, f'', adapted to engage with the slots in the integral collar of the spring-actuated plate, substantially as described.

In testimony whereof I affix my signature in 35 presence of two witnesses.

ORLANDO C. KETRING.
